Attorney

UNITED STATES PATENT OFFICE.

WILLIAM C. S. MAYS, OF CRANSTON, RHODE ISLAND, ASSIGNOR TO MAYS MANUFACTURING CO. INC., OF PROVIDENCE, RHODE ISLAND, A CORPORATION OF DELAWARE.

PENCIL.

Application filed November 13, 1920. Serial No. 423,960.

To all whom it may concern:

Be it known that I, WILLIAM C. S. MAYS, a citizen of the United States, residing at city of Cranston, in the county of Providence and State of Rhode Island, have invented certain new and useful Improvements in Pencils, of which the following is a specification.

This invention relates to improvements in mechanically fed lead pencils, and has for its object to provide an improvement in the construction of lead-propelling pencils, which is simple, practical and inexpensive in construction and which is made of the minimum amount of parts.

The nature and advantages of the invention will be better understood when the following detail description is taken in connection with the accompanying drawings, the invention residing in the combination and arrangement of parts as claimed.

In the drawings forming part of this specification, like numerals of reference indicate similar parts in the several views and wherein:

Figure 1 is a sectional side elevation of my improved pencil.

Figure 2 is a sectional elevation showing the rotatable unit as removed from the shell of the pencil, which includes the ejector carrier, the magazine, and the operating cap or end.

Figure 3 is a detail illustrating the eraser carrying cup with the eraser mounted therein.

Figure 4 is a detail illustrating the tube having the ejector operating helical slot therein.

Figure 5 is a detail illustrating the lead ejector.

With reference to the drawings, 10 designates the outer shell or body of a pencil, which is pointed at one end as at 11. Within this body is fixed the rigid ejector-operating member 12 which is preferably made in tubular form and provided with a helical groove 13 for receiving the uttermost end of the ejector. The lower end 14 of this tube is fixed in a central hole in the collar 15 and this collar in turn is secured to the inner face of the shell by means of pins 16, or otherwise.

A carrier for the ejector member is formed

of the tube 17 having its lower end 18 split as at 19 and supported by the tapering walls 55 of the shell. This carrier tube extends up through the center of the helical tube 12 and is provided with a collar or outwardly extending flange 20 at its upper end, which collar is fixed in the rotatable tubular magazine 21 providing a closure for the bottom of the same. The upper end of this magazine tube is provided with a cap-shaped operating member 22 which fits tightly over the end of the same and provides means 65 whereby this unit which includes the magazine tube 21 and the ejector carrier 17, may be rotated relative to the outer shell or body 10 and the helix 12.

This ejector carrier is provided with a 70 longitudinally-disposed slot 23 leading inwardly from its upper end and through which slot extends the outturned end 24 of the ejector member 25, the body portion of which ejector is designed to be carried in 75 the tube 17, its lower end being adapted to engage the upper end of the lead 26 in the outer end of the carrier and advance the lead, when desired.

Beneath the lower end of the helix 12 I 80 have formed a protuberance or shoulder 27 which serves to securely lock the ejector carrier tube in position against being drawn outwardly by any movement on the operating handle 22, after the collar 15 at the 85 lower end of the helix has been secured to the walls of the outer shell. In other words the rotatable unit including the cap 22, the magazine 21, and the ejector carrier 17, could all be withdrawn from the shell 10 if 90 it were not for this locking protuberance 27 formed in the ejector tube below the fixed collar 15.

In some instances it is found to be of advantage to provide a cap 28 which is adapted 95 to fit into the upper end of the magazine chamber 21 and to carry an eraser 29 which will be exposed for use when cap 22 is withdrawn from its tube 21.

The device is extremely simple, inexpensive and practical in construction.

The foregoing description is directed solely towards the construction illustrated, but I desire it to be understood that I reserve the privilege of resorting to all the 105 mechanical changes to which the device is

2
susceptible, the invention being defined and limited only by the terms of the appended claims.

I claim:

- 5 A pencil comprising an outer shell tapered at one end, a rigid tubular member within the shell and having a lateral spacing element stationarily secured thereto and extending outwardly therefrom to contact with
- 10 the inner walls of the shell and to maintain said member out of contact with said walls, said spacing element being fixedly secured to said shell whereby said tubular member is made stationary relative to the shell, said
- 15 tubular member having a helical groove therein extending substantially throughout its length, a rotatable slotted tube extending

through said tubular member and having one end terminating at the pointed end of the shell, a lead ejector slidable in said slotted tube and having a portion thereof extending through the slot in said tube into the helical groove of the said tubular member, and a member on the upper end of said slotted tube to engage the upper end of said tubular member for limiting the downward movement of said slotted tube and means at the other end of said slotted tube to contact with the lower end of said tubular member for limiting the upward movement of said slotted tube.

In testimony whereof I affix my signature.

WILLIAM C. S. MAYS.
